UNITED STATES PATENT OFFICE.

JOHN STANISLAUS WORZALLA, OF STEVENS POINT, WISCONSIN.

SWING.

1,266,744.

Specification of Letters Patent. Patented May 21, 1918.

Application filed January 10, 1917. Serial No. 141,590.

To all whom it may concern:

Be it known that I, JOHN S. WORZALLA, a citizen of the United States, and a resident of Stevens Point, in the county of Portage and State of Wisconsin, have invented a new and Improved Swing, of which the following is a full, clear, and exact description.

My invention relates to a swing of the type in which the seat is supported on hangers mounted to swing in a foldable frame.

The general object of the invention is to provide a reversible seat formed of variously connected elements carried by the hangers and arranged so that the seat may be positioned at either side of the hangers.

Further objects of the invention are to provide in connection with the reversible seat, novel means to firmly sustain the same in either position; and to provide a construction that will permit of the seat elements being folded within the plane of the hangers so that the swing when folded will occupy the minimum space.

The invention will be particularly explained in the specific description following.

Reference is to be had to the accompanying drawings forming a part of this specification in which similar reference characters indicate corresponding parts in all the views.

Figure 1 is a perspective view of a swing embodying my invention;

Fig. 2 is a transverse vertical section of the folded swing;

Fig. 3 is a sectional side elevation of the seat and a portion of the hangers;

Fig. 4 is a view similar to Fig. 3 but showing the seat reversed;

Fig. 5 is a face view of one of the stop plates for the seat;

Fig. 6 is a detail in side elevation showing a novel buffer applicable to the legs at the bottom thereof to prevent creeping of the frame;

Fig. 7 is a similar view showing the buffer under compression due to the strain caused by movements of the swing.

In constructing a swing embodying my invention, a suitable supporting frame is provided which in practice consists of side frame members or legs consisting of side bars 10 having cross bars 11 at the bottom, and cross bars 12 near the top, the adjacent side bars of the opposite frames being connected by articulated braces 13 of known form. The side frames or legs are pivotally

connected at their upper ends by eye-bolts 14, whereby one side frame may swing with the other to lie in the same plane. Hanger bars 16 are suspended in the supporting frame preferably through the medium of eyes 15 engaging the eye-bolts 14. The hangers 16 may be connected by cross bars 17 near the top.

The numeral 18 indicates the bottom or seat proper and 19 the back thereof. The side bars 20 of the seat 18 are pivotally connected near their front ends with the lower ends of the hangers 16 by pins or bolts 22, and the rear ends of said side bars 20 are pivotally connected as at 22 with the lower ends of the side posts 21 of the back. Arms 23 are pivotally connected at the forward ends with the hangers 16 above the pivots 22 of the seat 18, the said arms and said seat being disposed between the respective hangers. The rear ends of the arms 23 are pivotally connected with the upper ends of the back 21.

Onto each arm 23 is secured a plate 24 which has a hole 25 to receive the pivot bolt or pin 26 of the arms 23, and the plate is formed with one or more screws holes 25^a to receive screws for securing the plate to the adjacent arm 23 to swing with the latter. The numeral 27 indicates the pivotal connection between the arms 23 and the back 21. The plates 24 project above and below the arms 23 when the seat is in position for use and the projected members present shoulders or edges at each side of the pivotal connections with the hangers, whereby the projecting ends will constitute stops to engage fixed stops 28 secured to the hangers 26 at the inner sides thereof below and approximately in alignment with the pivots 26. Said stops 28 may be in the form of screws as indicated.

By the described arrangement, the seat 18 and the arms 23 may have a pivotal movement from one side of the hangers 16 to the other and their movements will carry the back 21. Thus, as shown in Figs. 3 and 4, the seat may be reversed and positioned at either side of the hangers and in either position the seat will be firmly supported by engagement of the plates 24 with the stops 28. Moreover, the plates 24 constitute friction elements between the arms 23 and the hangers 16. When the swing is not required for use the legs 10 may be folded one within the other and the hangers 16 within the plane of the legs. Also, the complete seat may be

folded into a vertical position within the plane of the legs as shown in Fig. 2 in which position the friction plates 24 will sustain the seat.

5 As is well known the spread legs of the swing constituting the supporting frame tend to shift under the action of the swing, there being a shifting force exerted on the forward legs by the forward movement of 10 the swing and a similar action on the rear legs in the rearward movement of the swing. To prevent shifting or creeping of the legs I provide resilient buffer blocks 29 preferably of rubber. The under side of each 15 block is beveled or inclined so that one end of the block forms a bearing terminal, and a clearance space is presented extending from said end toward the opposite end. Usually, the beveled surface is produced by 20 forming the blocks of reduced thickness at one end, the upper surface being horizontal to mate the horizontal under surface of the leg. The blocks are reversed on the front and back legs so that the bearing terminals 25 thereof of the front legs will be at the front and the bearing terminals of the rear legs will be at the rear. The shocks to which the front legs are subjected by the swing by a forward movement thereof will 30 compress the front blocks, increasing the gripping action of the front ends thereof, the reverse action taking place on the rear blocks. A comparison of Figs. 6 and 7 indicates the form of the block before the 35 shock and when under compression, respectively.

Having thus described my invention I claim as new, and desire to secure by Letters Patent:

40 1. In a swing, hangers, means mounting the hangers for swinging movement, a seat between the hangers and pivoted near the front end thereof to swing to a position at either side of the hangers or a position 45 between the hangers and in the plane thereof, a back pivoted at its lower end to the rear end of the said seat, arms pivoted at the front ends thereof to the hangers at the inner faces of the latter above the seat 50 pivots, the said arms being adapted to swing to either side of the hangers or to an intermediate position in the plane of the hangers, the rear ends of said arms being pivoted to the upper end of the said back, said back 55 being swingable with the seat and arms to either side of the hangers or to a position in the plane of the hangers, stops on the hangers at the inner surfaces thereof beneath the pivots of the arms, and plates 60 interposed between the outer faces of the arms and the hangers and swingable with the arms with the adjacent pivots of the arms as axes, the said plates presenting ends projecting beyond the upper and lower surfaces 65 of the arms when the seat is in position for

use, the said projecting ends presenting edges either of which is engageable with the fixed stops on the hangers to sustain the seat at either side of the hangers.

2. In a swing, hangers, means mounting the hangers for swinging movement, a seat between the hangers and pivoted near the front end thereof to swing to a position at either side of the hangers or a position 75 between the hangers and in the plane thereof, a back pivoted at its lower end to the rear end of the said seat, arms pivoted at the front ends thereof to the hangers at the inner faces of the latter above the seat pivots, the said arms being adapted to swing to either side of the hangers or to an intermediate position in the plane of the hangers, the rear ends of said arms being pivoted to the upper end of the said back, 80 said back being swingable with the seat and arms to either side of the hangers or to a position in the plane of the hangers, fixed stops on the hangers adjacent to the pivots of the arms, and oppositely disposed stop members on each arm, one of the stop members of 85 each arm being engageable with the fixed stop to sustain the seat positioned at either 90 side of the hangers.

3. In a swing, a support, hangers swingable on the support, a foldable seat structure including a seat, side arms, and a back pivotedly connected with the seat and arms, said seat and arms being pivoted to the hangers to be positioned at either side thereof, a fixed stop on each hanger and a stop 95 rigid with each side arm to turn therewith, each of said stops, when the seat is in position for use, presenting lateral surfaces above and below the adjacent pivot of the arm and disposed toward the fixed stop so that either of the said surfaces of each stop 100 will engage the adjacent fixed stop as the seat is positioned at one side or the other of the hangers.

4. In a swing, a support, hangers mounted to swing on the support, a seat between the hangers and pivoted near the front end thereto, side arms above the seat and pivoted near the front ends to the hangers, a back pivotedly connected at its lower end 110 with the seat and at its upper end with the side arms, said seat, arms and back being swingable from one side of the hangers to the other, and co-acting stop elements on the hangers and side arms engageable with 115 each other when the arms are disposed at either side of the hangers.

5. In a swing, a support, hangers mounted to swing on the support, a seat between the hangers and pivoted near the front end thereto, side arms above the seat and pivoted near the front ends to the hangers, a back pivotedly connected at its lower end 120 with the seat and at its upper end with the side arms, said seat, arms and back being 125

swingable from one side of the hangers to the other, a fixed stop on each hanger beneath the pivots of the side arms, plates between the side arms and hangers, the adjacent pivots of the arms passing through said plates, and means rigidly fastening the said plates to the side arms, said plates pre-

senting members projecting above and below the arms when the latter are on either side of the hangers, either of said members 10 being adapted to engage the fixed stops on the hangers according to the position of the arms at either side of the hangers.

JOHN STANISLAUS WORZALLA.
